UNITED STATES PATENT OFFICE.

CONRAD GAUTSCH, OF BERLIN, GERMANY.

METHOD OF EXTINGUISHING FIRES IN TELEPHONE INSTALLATIONS.

1,023,107.

Specification of Letters Patent.

Patented Apr. 9, 1912.

Application filed January 28, 1911. Serial No. 605,262.

To all whom it may concern:

Be it known that I, CONRAD GAUTSCH, a subject of the King of Bavaria, and resident of 9 Berchtesgadenerstrasse, in Berlin, in the Kingdom of Prussia, German Empire, have invented certain new and useful Improvements in Methods of Extinguishing Fires in Telephone Installations, of which the following is a specification.

This invention relates to a new method of extinguishing fires, particularly fires which occur in telegraph, telephone and similar installations. In such installations bundles of cables are often placed in casings or boxes, and if a fire breaks out due to short circuits or the like or is produced in effecting repairs (with a soldering torch) or in other ways, they are not easily accessible for the purpose of extinguishing the fire or preventing the fire from spreading. Further, water must not be used for extinguishing such fires as it would increase the danger of short circuits, and as the bundles are so compact the introduction of other known extinguishing means is impracticable.

The object of this invention is to provide a convenient and effective method of extinguishing such fires. For this purpose, I provide a system of conduits or pipes for conducting two different extinguishing gases to the point of the fire and permitting said gases to combine at the point of leaving the conduits or pipes; the gases employed being such that they do not support combustion and that when they combine they form a dry dust like powder which is deposited upon the fire and the accessible adjacent parts of the installation.

As in practice it would be inadvisable continually to retain the gases in the pipes or conduits in consequence of leakage, and the injurious effect of the gases on the pipes, the system of pipes is therefore normally filled with air, and means are provided for the purpose, in the case of fire, of first expelling the air in the pipes into the atmosphere by means of the gases, and when the pipes are full of the gases to discharge these on the fire.

The extinguishing gases which have been found most advantageous are ammonia and carbonic acid or ammonia and sulfur dioxide, that is, an ammonia gas and an acid gas.

In the accompanying drawings is illus-

trated by way of example, an installation and apparatus by which this method may be carried out, but it will be understood that various changes may be made in the installation, apparatus and method without departing from the scope of the invention as claimed.

Figure 1 is a diagrammatic vertical section of a building provided with the apparatus for carrying out the invention; Fig. 2 is a diagrammatic transverse section of the operating tables, the boxes and the cables; Fig. 3 shows a sectional view of a three way valve used in the apparatus in the pipes 9 and 12; Fig. 4 illustrates a valve one of which is used at the upper end of each pipe 9 and 12, the same being a two way valve; Figs. 5 and 6 are longitudinal sectional views of suitable nozzles for discharging the gases at the proper points; Fig. 7 illustrates a side elevation of a so-called mixing stud adapted to be used with the nozzle of Fig. 5; Fig. 8 illustrates a side elevation showing the method of grounding and insulating the gas conduits or pipes; Fig. 9 illustrates a sectional view showing the grounding and insulating means for the valve operating rods; and Fig. 10 illustrates the arrangement of the conduits or pipes in pairs.

Referring to Fig. 1, the telephone installation is shown arranged in a house having windows 1 and a basement 2. The operating boxes 3 with the respective tables 4 may be arranged in the different stories as shown. In the basement are provided the bottles 5 for one gas, and the bottles 6 for the other gas, each of which bottles is controlled by a valve 7. The bottles 5 all terminate in a common collector 8 to which is connected a pipe 9 extending upwardly to the various stories and provided with branch pipes 10 leading to the operating boxes 3. The bottles 6 terminate in a common receptacle 11, to which is connected a pipe 12 extending upwardly through the various stories of the building, side by side with the pipe 9, (Fig. 10) and the pipe 12 is provided with branch pipes 10 similar to the pipe 9.

From the branch pipes 10 (Fig. 2) of both the main pipes 9 and 12, branch pipes 13 lead into the operating boxes 3 and under the table 4. The branch pipes 13 are provided with mouth pieces or nozzles 14 introduced into the cable bundles 15. Each of the branch pipes 10 connected to the main

pipe 9 and each of the branch pipes 10 connected to the main pipe 12 is controlled by a two-way valve shown in detail in Fig. 3. This valve is advantageously provided with 5 two sets of ports for the control of gas from the main pipes 9 and 12, or two such valves may be used, one for each of the main pipes 9 and 12 and their corresponding sets of branch pipes 10 and 13.

10 Each valve 16 is adapted, when in the normal position, as illustrated, to establish communication between the main pipes 9 or 12 and the atmosphere by means of the pipe 18 which passes through the walls of 15 the building as shown. Two such pipes 18 are provided when one common valve is used for each of the main pipes 9 and 12. When the valves 16 are turned to effect the 20 position corresponding to Fig. 3, communication is established between the main pipes 9 and 12 and each of the lateral branch pipes 10 and therefore with the pipes 13 and the nozzles or mouth pieces 14.

It will be understood that the branch 25 pipes 13 illustrated in Fig. 2, are in duplicate, and arranged side by side, so that each of their extremities may be brought together to form a common mouth piece or nozzle as illustrated in Fig. 5. One set of branch 30 pipes 13 is connected through the respective valves 16 with the main pipe 9, and the other set through valve 16 with the main pipe 12, so that this one set of pipes serves to convey the ammonia gas while the other 35 set serves to convey the acid gas, such as sulphur dioxide.

In order to control the valves 16, the rotatable parts 19 thereof are each provided with a toothed wheel 20 which engages with 40 a toothed rod 21 which may be pushed up from the basement when the valves are to be operated. The two way valve 17 shown in Fig. 4 has the pipes 9 or 12 connected to it directly, said valve having the rotatable part 45 19' having a port, adapted to communicate with the pipes 9 or 12 and the pipes 10, or with the pipes 9 or 12 and the pipe 18' meant for the discharge of air within the system. The valve 17 is operated by the 50 toothed rod 21 and toothed wheel 20, and is intended for use at the upper ends of the pipes 10 and 13.

The two gases are kept entirely separate from each other in the separate main pipes 55 9 and 12 and the pairs of branch pipes 10 and 13, and are not allowed to mix until they issue from the nozzles.

Various styles of nozzles may be used, Figs. 5 and 6 showing suitable examples. 60 In Fig. 5 a nozzle 14 is illustrated having the separate sets of branch pipes 13 which are placed side by side and at the end are inclined toward each other and joined together. A closing cap 22 may be placed on 65 the top of the nozzle. Mixing studs 23 may

be provided at the point of junction of the respective branch pipes 13 to have knife edges 24 for distributing the gases in streams. In Fig. 7 is illustrated one of the said studs in front view.

In the form of nozzle 14^a shown in Fig. 6, the separate branch pipes 13 are placed one inside the other and the mixing studs are replaced by spiral ribs or grooves 25, 26, running in opposite directions.

70 In order to protect the gases against free electric currents the whole system of pipes is divided into sections wherever necessary and insulating pipes 27 (see Fig. 8) inserted between the sections, the sections being connected to earth 28 by means of the conductor 29. In Fig. 9 is shown a section of the rod 21 having an insulating piece 30 for the same purpose, a section of the rod being connected to earth 31 by the conductor 32. It will be understood that by such means should current reach the pipes or rods it will be immediately conducted to earth. This arrangement is entirely effective and also protects the operator from any 90 accidental shock and renders insulating handles, mats and the like, unnecessary.

75 The operation of the apparatus is as follows: The separate main pipes 9 and 12 which are connected to suitable bottles 5 and 6 for example for ammonia and carbonic acid respectively, when the fire breaks out are filled with the gases by opening the valves 7 and the air which may have collected in the pipes is driven out through the 100 outlet pipes 18 by the said gases. When the air is entirely driven out the valves 16 are rotated by means of the rods 21, to direct the gases into the branch pipes 10 and finally through the respective sets of branch 105 pipes 13 into the nozzles or mouth pieces 14. Here the extinguishing gases combine right at the point of application and form upon the fire and upon the adjacent parts of the installation, a cover of a fine dry powder 110 produced by the combination of the separate gases referred to.

Means are provided for slowly drawing off the excessive quantities of gases through 115 openings in the bottom of the apparatus, boxes 3 or of the operating tables 4, a fan 33 being used if desired. Pipes 34 are connected to the casing of the fan and terminate in branches 35 which project into the boxes 3, the gas being discharged into the atmosphere through the pipe 36.

I claim—

1. A method of extinguishing fires occurring in electric cable and circuit installation consisting in separately conveying different 125 extinguishing gases which when mixed form a solid, dust-like salt, from a place of storage and introducing them to the fire to be extinguished, and in allowing the gases to mix just before encountering the fire where- 130

by a solid dust-like salt is produced and deposited on the fire and upon the accessible adjacent parts of the installation.

2. A method of extinguishing fires in bundles of cables consisting in separately introducing different extinguishing gases, which when mixed form a solid dust-like salt, into the interior of the bundles of cables, and permitting the gases to unite in the interior of the bundles of cables to form a solid dust-like salt which is deposited upon said cables and upon the accessible adjacent parts of the installation.

3. A method of extinguishing fires occurring in bundles of electric cables consisting in conveying extinguishing gases which when mixed form a solid, dust-like salt, from a distant place through suitable conduits to the place where the fire has broken out, first expelling the air from the conduits by the gases passing through said conduits and in mixing the gases prior to their escape from the conduits.

4. Method of extinguishing fires occurring in bundles of electric cables, consisting in conveying extinguishing gases, which gases when mixed form a solid dust-like salt, from a distant place through suitable conduits to the place where the fire has broken out, and in mixing the gases prior to their escape from the conduits and in carrying off the excess of gases, substantially as described.

5. A method of extinguishing fires occurring in bundles of electric cables consisting in separately conducting gases which when mixed produce a solid dust like salt, and in mixing said gases at a point where the dust like salt will be deposited on the fire.

In testimony whereof, I have signed my name to this specification in the presence of two subscribing witnesses.

CONRAD GAUTSCH.
